BROWN, OF SPRINGDALE, CONNECTICUT.

GENERATING AND CONTROLLING SYSTEM FOR RADIOTELEPHONES.

Application filed November 14, 1922. Serial No. 600,867.

My invention relates to electrical signal transmitting apparatus and more particularly to generating and controlling systems utilized in the transmission of intelligence by radio telephony.

The primary object of my invention is to provide a radio transmitting system of greater effectiveness than has heretofore been common in the art. Further objects are to augment the economy of operation of such radio transmitters, to provide controlling instrumentalities which are susceptible of easy adjustment, and to improve the accuracy of speech transmission and reproduction. Moreover, my invention involves no elements which are erratic in operation or difficult of manipulation and consequently as a whole it is eminently suitable for continuous and practical service.

I have discovered that by designing the several portions of a radio telephone system along the novel lines described in the following specification, and by arranging the component parts into a harmoniously-operating whole, the apparatus becomes capable of transmitting radio telephonic signals over great distances with the application and consumption of only small or moderate amounts of power. Also, I find that by properly proportioning and arranging the control circuits of my transmitter, this unusually economical transmission can be attained without losing accuracy or fidelity of reproduction of the transmitted speech.

The construction and operation of my system may be more clearly understood by reference to the drawing, which is a conventional wiring diagram of one form of the transmitter which I prefer to employ. In this drawing I have not shown mechanical details such as the methods of mounting; it will be understood by those skilled in the art that great latitude may be allowed in such matters without departing from the spirit or losing the utility of my invention. The various elements are indicated by their usual diagrammatic representations, and the drawing, in connection with the following description, will serve to define to a radio engineer the exact character and arrangement of apparatus, embodying my invention, which I have found to give satisfactory results.

Referring specifically to the drawing, it

will be seen that the transmitting system 55 may conveniently be considered in five portions, viz., the control, the voice amplifier, the modulator, the oscillator and the radiator. Certain elements, in particular the power sources, are common to several of these 60 arbitrary divisions, but the general operation of each part may be analyzed independently of the others.

The control system comprises the microphone M, into which are spoken the words 65 to be transmitted, the direct current source E1 whose output is moulded into electric undulations (corresponding to the sound waves of speech) in passing through the microphone M, the modulation transformer MT 70 and the leak resistance R1. The source E1 may conveniently be a 4-volt battery and the microphone M a standard long-distance telephone transmitter. The transformer MT should be designed to develop the maximum 75 potential variation possible without introducing distortion; I have found that a primary to secondary impedance ratio of 60 to 600 000 ohms is satisfactory, and that a substantial improvement in quality of speech 80 reproduction may be obtained by connecting the non-inductive leak resistance R1, of about one megohm, in shunt to the secondary winding.

The secondary terminals of the modulation transformer MT lead directly to the grid and negative filament terminal of the vacuum tube VA which is the prime element of the voice amplifier system. This tube should be of the three-element grid-control 85 or audion type, but capable of handling more power than the tubes ordinarily used for radio reception; I have found a standard 5-watt triode to be satisfactory for this purpose.

Associated with the voice amplifier tube VA is the grid circuit battery E2, which may have a voltage of slightly over 20 and must have its negative terminal connected to the grid. This battery serves to maintain the grid at a potential substantially more highly negative than any part of the filament, and this not only prevents energy loss by reason of current flowing across the vacuous space from the grid to the filament but also minimizes distortion of the amplified speech-carrying currents.

The filament of the voice amplifier tube

VA is heated by current from the battery E4 passing through the rheostat R4 which regulates the degree of incandescence of the filament. Battery E4 may be a group of 4 storage cells in series, delivering continuously about $2\frac{1}{2}$ amperes at 8 volts potential difference. The negative terminal of this battery should be connecting to earth, as shown. The rheostat R4 may have a total resistance of about 10 ohms.

The plate circuit of the voice amplifier tube VA is supplied with direct current energy from the generator DC, to the positive terminal of which it is connected by way of the non-inductive resistor R2 and the impedance coil I2. The negative terminal of the generator DC is connected to earth, thus completing the filament-plate circuit of the tube VA. This generator produces current at a potential of from 700 to 1000 volts, for the larger tubes of the system; the voice amplifier tube requires only from 350 to 500 volts on its plate (positive with respect to the filament) and consequently I prefer to reduce the potential applied in this circuit by inserting the resistance unit R2. In general the unit R2 has a resistance approximately equal to that of the tube, or in this case about 10,000 ohms. The plate current, under these conditions will be about 40 milliamperes normal, which increases to 50 or 55 milliamperes when speech is transmitted.

It will be understood that voice-controlled undulating currents reproduced by the microphone and battery E1 will be increased in potential by the transformer MT and applied to the grid or control electrode of the voice amplifier tube VA. The magnifying function of this tube will result in augmented variations in the plate circuit containing the resistance R2 and the choke coil or impedance I2. The inductive reactance of the coil I2 will prevent dissipation of these variations in the plate circuit and will cause the impression of intense fluctuations of potential upon the coupling condenser FC3 which leads directly to the input circuit of the modulator vacuum tube MO.

This modulator tube is the heart of the third portion of my transmitter, and may be (in the particular instrument herein described) a standard 50 watt audion power tube. As shown in the drawing, its grid is connected to ground through the leak resistor R3, which may have a value of from 10 to 15 thousand ohms, and the battery E3. The battery E3 impresses a constant negative potential on the grid of the modulator tube, and may conveniently have an electromotive force of 40 volts.

The filament of the modulator tube may be heated by means of alternating current supplied from the ordinary lighting lines shown at AC. This power source is con-

nected through the switch SW to the primary P of a step down transformer ST, the secondary terminals of which are applied directly across the filament of the modulator tube MO. This transformer should be constructed to reduce the AC voltage of the line (which is usually of about 110 volts) to a value of approximately 10.5 volts, which is suitable for the filament circuit. I prefer to ground the mid point of the secondary of this step down transformer, and to connect across each half of the secondary coil thus divided a fixed condenser (shown in the drawing at FC4 and FC5 of about 0.001 microfarad capacitance. It will be seen that the filament is effectively grounded for direct current through the windings of the transformer secondary and that by the provision of the condensers FC4 and FC5 it is also effectively grounded for radio frequency oscillations, which are enabled to pass around the secondary winding to earth directly through these condensers. On the other hand, these condensers are of quite high impedance to alternating current variations of audible frequency, as is also the secondary winding of the step down transformer, and it is to this novel balance of electric constants that I attribute a substantial portion of the superior results obtained by the use of my system.

The plate circuit of the modulator tube MO is supplied with about 125 milliamperes of direct current at from 700 to 1000 volts, directly from the high potential generator DC, the negative terminal of which is grounded, its positive terminal being led to the plate of the modulator tube through the impedance coil I1. For this coil, as well as for the impedance I2 I prefer to use a closed iron-core choke coil having an inductance of approximately two henrys.

The intensified voice current potential variations applied to the modulator tube grid through the condenser FC3 serve to control the effective plate resistance of this modulator tube throughout a wide range. As shown in the drawing, the high potential point of the modulator plate circuit is connected directly to the plate of the oscillator tube OS through the high frequency choke coil HFC and supplies this tube with its normal plate current of about 125 milliamperes. This coil, having an inductance of about 3 millihenrys, effectively prevents the leakage of radio frequency oscillations through the modulator tube, but permits the varying resistances of the modulator to abstract from, or, by reason of the reactance of I1, to feed into, the oscillator plate circuit (at audible frequencies) varying amounts of electric energy at a rate which depends entirely upon the instantaneous intensity of the voice vibration to be transmitted. It will be seen at once that if the

modulator tube has, for the moment, a low resistance, it will draw from the oscillator plate a considerable portion of the energy available for generating radio frequency currents. On the other hand, if the modulator tube remains at a very high resistance, the oscillator tube plate potential will be practically unaffected by it and the oscillator system will generate radio frequency currents of maximum amplitude, practically as though the modulator were entirely disconnected. Intermediate values of modulator tube resistance (produced by intermediate values of the applied voice currents) will result in intermediate values of the generated radio frequency oscillations, and thus of the intensity of the radio frequency currents produced in the antenna circuit. Consequently the intensity of the radio waves transmitted may be exactly and quantitatively controlled throughout a wide range by the speaking voice or by other sounds which impinge upon the microphone M. Stored energy in the impedance I1 may, on a sudden increase of modulator tube resistance, practically double the oscillator plate voltage for an audible frequency period.

The filament of the oscillator tube OS is connected in parallel with that of the modulator tube MO and supplied from the alternating current source which has already been described. I prefer to use a 50 watt power audion for the oscillator as well as for the modulator; as will be seen from the drawing this filament circuit is grounded through the step down transformer secondary and the condensers FC4 and FC5 exactly as in the case of the modulator tube. The oscillator plate circuit is fed with direct current from the source DC through the choke coil I1 and the high frequency coil HFC, the return path being through the ground connections of the generator and oscillator filament. From the oscillator plate a branched oscillating circuit to ground is provided through the fixed condenser FC2 (which may have a capacitance of about 0.002 microfarads) and the branch resonant circuit consisting of the elements L1 and VC2. In my preferred arrangement L1 is a variable tuning coil of approximately 0.09 millihenry maximum inductance, and VC2 is a variable condenser having a range up to about 0.00025 microfarad capacitance. Such a coil may be made by winding 16 turns of #18 wire on a 4½ inch diameter cylinder. It will be understood that the constants here given have been chosen for operation at comparatively short wave lengths, in the neighborhood of 200 meters. From the branch resonant circuit just described a connection is made directly to ground. The antenna-to-ground circuit is inductively coupled to the coil L1

through the secondary coil L2, one end of which leads directly to ground and the other end of which is connected through a tuning condenser VC1 and a radio frequency ammeter RFA to the antenna A. The coil L2 and the condenser VC1 must be chosen with regard to the constants of the aerial with which they are to be used; with an antenna having a capacitance of 0.00038 microfarad I found that the condenser VC1 should extend upward to a maximum of 0.0004 microfarad and that the inductance L2 may have a value of 0.03 millihenry, which may be secured by winding 14 turns of #18 wire, somewhat spaced, upon a tube of 4½ inch diameter.

Oscillations generated in the plate circuit inductance L1 will be inductively transferred to the aerial circuit coil L2, thus resulting (when the antenna circuit is tuned) in a substantial radio frequency current between aerial and ground. As is well known, such a current gives rise to the desired electro-magnetic waves which are to be transmitted.

The grid circuit of the oscillator OS extends to ground through the variable coil L3 and the fixed condenser FC, which latter is shunted by a leak resistor R5. The coil L3 is inductively coupled to the antenna coil L2, and is adjusted in conjunction with the condenser FC1 so as to control the oscillator grid potential in such phase and intensity that electric oscillations will be maintained in the plate and aerial systems. I have found that L3 may conveniently be a coil similar to that described for the plate circuit L2, and that the condenser FC1 should have a capacitance of about 0.002 microfarad. The resistor R5 may conveniently have a value of approximately 5000 ohms; its function is mainly to prevent the oscillator grid from attaining a high negative charge which would choke the oscillator system.

The operating adjustments of my system are notably simple and stable and may be easily determined by noting the type of operation which is characteristic of the various parts when properly co-ordinated. Although I have given in the foregoing a number of numerical values of various constants which I have found by experiment to be suitable for a particular transmitter operating at approximately 800 volts oscillator plate potential and delivering 2.8 amperes into a 12-ohm antenna at 1,500,000 cycles, it will be understood that I do not wish to be understood as limiting my invention to the particular constants cited, nor even to the specific circuits illustrated. Indeed, many modifications will at once occur to one skilled in the art; for example, the power may be changed by the choice of vacuum tubes of sizes larger or smaller than those cited in the above (the

- circuit constants necessarily being changed to correspond with the altered power conditions) or operation may be effected at wavelengths quite different from that chosen in the example given. Further, it is feasible to use other forms of oscillation circuit, common in the art, in conjunction with the voice-amplifier and modulator system I have illustrated, or to utilize radio frequency amplifiers between the oscillator and the aerial systems for the purpose of augmenting the output power. Whatever circuit variations are made, it is essential to maintain the proportions of the various choke or impedance coils and condensers such that they will offer suitable reactance to the currents of various frequencies developed in the several parts of the system, as exemplified in the foregoing.
- 20 I have found certain easily observed features to be characteristic of my system when used under the conditions set forth. These are generally applicable, though to varying extents as the circuits are modified, to arrangements which embody my invention, and may be stated as follows:
- 25 A. The plate current of the voice-amplifier tube increases when the microphone is spoken into.
- 30 B. As the voice amplifier plate current increases, the average modulator tube plate current decreases, as may be shown by its change of color from cherry-red to black or grey.
- 35 C. As the modulator tube plate current falls off, the oscillator plate current in general increases.
- 40 D. If the radiating-load of the aerial circuit is withdrawn, the total plate current though oscillator and modulator tubes falls to as little as $\frac{1}{2}$ its normal value.
- 45 E. The intensity of modulation is so great as to produce mechanical vibration of the oscillator tube, so that the transmitted sounds can be heard reproduced in the air within a zone of several feet about the oscillator.
- 50 F. The use of alternating current for heating the filament of the modulator and oscillator tubes, together with the system of audio impedances and radio frequency by-

pass capacitances provided in the system as shown, gives a substantial increase in overall efficiency as contrasted to direct-current filament heating.

It will be understood that in the specification and claim I have used the terms "audio frequency" and "radio frequency" in their normal senses, i. e., audio frequency refers to the rate of electric variations corresponding to the sounds to be transmitted (ordinarily between the limits of 15 cycles and 20 000 cycles per second) and radio frequency refers to the rate of electrical oscillations to be radiated as electromagnetic waves (ordinarily between the limits of 15 000 and 3 000 000 cycles per second). I do not desire to be limited to any specific numerical values of either frequency, but in general intend that "radio frequency" shall signify the frequency of the carrier wave utilized and "audio frequency" the frequency of the modulations imposed thereon.

Having set forth the novel and useful results which may be obtained from radio transmitters embodying my invention, and having described in detail the construction and operation of one practical form of such transmitters, what I claim is:

A radio-telephone oscillator comprising an antenna, a ground connection, a condenser and an inductor serially connected between said antenna and said ground connection, a vacuum tube having a cathode, an anode and a control electrode, a circuit exterior to the tube from said anode to said cathode, a second circuit exterior to the tube from said control electrode to said cathode, a ground connection for said cathode, a second inductor coupled to said first-named inductor, a second condenser serially connected with said second inductor in said anode circuit, a third condenser in shunt to said second inductor, a third inductor coupled to said first-named inductor and connected in said control electrode circuit, a fourth condenser in series therewith in said circuit, a resistor in shunt to said fourth condenser, and means for varying the electrical constants of the circuit thus constituted, substantially as described.

VERNER A. HENDRICKSON.
